UNITED STATES PATENT OFFICE.

JOSEPH BIJUR, OF NEW YORK, N. Y., ASSIGNOR, BY MESNE ASSIGNMENTS, TO BIJUR MOTOR APPLIANCE COMPANY, A CORPORATION OF DELAWARE.

CONNECTING DEVICE FOR STORAGE BATTERIES.

1,334,883.

Specification of Letters Patent. Patented Mar. 23, 1920.

Application filed April 1, 1915. Serial No. 18,489.

To all whom it may concern:

Be it known that I, JOSEPH BIJUR, a citizen of the United States, and residing at 122 East 60th street, in the county of New York and State of New York, have invented a new and Improved Connecting Device for Storage Batteries, of which the following specification is a full disclosure.

This invention relates to connecting devices for storage batteries, and more particularly to the leads or conductors running to or from the batteries.

One of the objects thereof is to provide a reliable, efficient and durable connecting device of the above nature. Another object is to provide a device of the above nature in which the parts have a tight fit and are not subject to deterioration in use. Other objects will be in part obvious and in part pointed out hereinafter.

The invention accordingly consists in the features of construction, combinations of elements, and arrangement of parts, which will be exemplified in the construction hereinafter set forth, and the scope of the application of which will be indicated in the following claims.

In the accompanying drawing there is shown an embodiment of this invention in which:—

Figure 1 is a side elevation, certain parts being cut away to disclose the construction more clearly, and Fig. 2 is a detail sectional view along the line A—A of Fig. 1.

Similar reference characters refer to similar parts throughout both views of the drawings.

Referring now to this drawing in detail, there is shown at 1 a storage or secondary battery upon which is mounted a terminal member or part 2. This member is electrically connected with the battery and is preferably rigidly mounted thereon being connected with or formed integral with a portion of the battery. Member 2 is provided with a tapering recess 3, which preferably forms an opening extending entirely therethrough and is preferably arranged in an up and down direction, although, if desired, it may extend horizontally or otherwise. Member 2 is preferably formed of lead, at least at its outer portions, and has formed therein or thereon a member 4 of relatively hard metal such as copper or brass which

extends about recess 3 by means of a ring portion 5. This member not only increases the conductivity of the member 2, but being exposed to outward pressure as the tapering part, hereinafter described, is forced into the recess, is well adapted to stand such pressure and prevent deformation of the parts. The broad combination with these parts of a device of relatively hard metal exposed to pressure as a tapering plug is forced into the recess is not claimed herein, as it is claimed in the patent granted to me September 1, 1914, No. 1,108,883. There are, however, specifically different features in the present invention which in certain relations are of marked value, and one of which is embodied by the formation of the inner walls of the recess, as at 6, by a layer of relatively soft metal such as lead alloy.

The battery lead 7 which is here indicated as a flexible conductor 8, insulated at 9, has formed upon its end a member 10, the outer portion of which at 11 is preferably covered with lead. The end of member 10 takes the form of a tapered plug 12, preferably of hard metal, and so formed as to fit within the recess 3 extending beyond the same at the lower end as at 13 to permit it to make a free fit with the inner walls of the recess. The upper end of the plug 12 is provided with an internally threaded opening 14 with which there coacts a screw 15 bearing upon the upper surface of the member 2 by means of a washer 16, and thus adapted to draw the plug firmly into its seat in the socket and hold it rigidly in such position.

It may be noted that the outer portion of the plug 12 is preferably provided with a layer or coating 17 of lead or similar metal.

In the use of this device if it be desired to make connection with the battery the plug 12 is thrust within recess 3, and the screw 15 with its washer 16 inserted, as shown in Fig. 1 of the drawings, and tightened. This action forms an extremely close joint between the plug 12 and the soft walls of the recess in which it is seated. The outward or expanding pressure, however, to which these walls, and through them the ring portion 5, are exposed, which pressure may reach a high value, due to the wedging action of the plug, is effectively restrained by the hard metal portion, and the device thus guarded against deformation in shape

other than a truing up of superficial irregularities in its inner surface by the seating of the plug. It may also be noted that the inner walls of the recess are well adapted 5 to resist any action of the acid of the battery. It may also be noted that the tapered member 12 being of relatively hard metal forms secure threads for the screw 15, to coat with and thus permits any desired 10 pressure of contact to be attained.

As many changes might be made in the above construction, and as many apparently different embodiments might be made of this invention without departing from the 15 scope thereof, it is intended that all features herein described or shown in the accompanying drawings shall be interpreted as illustrative and not in a limiting sense.

Having thus revealed this invention, I 20 claim as new and desire to secure the following combinations of elements, or equivalents thereof, by Letters Patent of the United States:

1. In a connecting device for storage batteries, in combination, a member electrically and mechanically connected with the battery, a conductor, a member on the end of said conductor, one of said members being of tapered form and the other being 25 provided with a tapered recess in which said tapered member is removably fitted, and means adapted to force said tapered member within said recess and hold it therein, said recessed member comprising a portion 30 of relatively hard metal about said recess and having soft metal interposed between said hard metal and the outer surface of said tapered member.

2. In a connecting device for storage batteries, in combination, a member electrically and mechanically connected with the battery, a conductor, and a member on the end of said conductor, one of said members being of tapered form and the other provided 40 with a tapered recess in which said tapered member is removably fitted and said recessed member comprising a portion of relatively hard metal extending about said recess for a material portion of the length thereof and 45 having soft metal interposed between said hard metal and the outer surface of said tapered member.

3. In a connecting device for storage batteries, in combination, a member electrically and mechanically connected with the battery, a conductor, a member on the end of 55 said conductor, one of said members being of tapered form and the other provided with a tapered recess in which said tapered member is removably fitted and said recessed member comprising a portion of relatively hard metal extending about said recess for a material portion of the length thereof and having soft metal interposed between 60 said hard metal and the outer surface of

said tapered member, and means adapted to force said tapered member within said recess and hold it therein.

4. In a connecting device for storage batteries, in combination, a member electrically and mechanically connected with the battery, a conductor, a member secured to said conductor, one of said members being of relatively hard metal and having a tapered outer surface, and the other member 70 being provided with a tapered recess in which said tapered member is removably fitted, the walls of said recess being formed of soft metal and surrounded by a relatively hard metal member exposed to pressure as said tapered member is forced into position, and means adapted to force said tapered member within said recess and hold it therein.

5. In a connecting device for storage batteries, in combination, a member electrically connected to a storage battery and rigidly mounted thereon, said member being provided with a tapering recess, a battery lead, a member electrically and mechanically connected with said lead and tapered to fit said recess, a threaded device interposed between said members and adapted to force said second member within said recess and hold it therein, the inner walls of said recess being of soft metal, and a member of relatively hard metal extending about said recess and exposed to pressure from said tapered member through said soft metal as said tapered member is forced into said 100 recess.

6. In a connecting device for storage batteries, in combination, a member electrically connected to a storage battery and rigidly mounted thereon, said member being provided with a tapering recess, a battery lead, a member electrically and mechanically connected with said lead and tapered to fit said recess, a threaded device interposed between said members and adapted to force said second member within said recess and hold it therein, the inner walls of said recess being of soft metal, and a member of relatively hard metal extending about said recess and exposed to pressure from said tapered member through said soft metal as said tapered member is forced into said recess in the direction from 110 which it enters the same.

7. In a connecting device for storage batteries, in combination, a member electrically and mechanically connected with the battery, a conductor, a member secured to said conductor, one of said members being provided with a tapered recess and the other of said members being of relatively hard metal and adapted to enter said recess, a relatively hard metal part upon said 125

- recessed member extending about said recess and adapted to hold the same against substantial deformation, a portion of soft metal interposed between said first hard member and said last mentioned hard member, said soft metal having a tapering surface, and means adapted to force said first hard member within said recess and hold it therein.
- 10 8. In connecting device for storage battery leads, in combination, a member electrically and mechanically connected with the battery, a conductor, a member secured to said conductor, one of said members being provided with a tapered recess and the other of said members being of relatively hard metal provided with an outer layer of soft metal having a tapering form adapted to fit said recess, means adapted to force said outer member within said recess and hold it therein, and a part of relatively hard metal extending about said recess and exposed to pressure from said tapering member as the latter is forced into position.
- 25 9. In a connecting device for storage battery leads, in combination, a conductor provided at its end with a tapering plug, a metallic member electrically connected with said battery and provided with an insert of relatively hard metal having an aperture of substantially the same effective taper as that of said plug, means adapted to secure said plug within said aperture, and means forming a coating of soft metal between the outer surface of said plug and the inner surface of said insert.
- 30 10. In a connecting device for storage batteries, in combination, a member secured to one of the battery terminals and pro-
- vided with an aperture having an inner surface of soft metal, said member being provided with an extension in the direction of the axis of said aperture whereby the inner surface of said aperture is increased.
11. A terminal connector for storage batteries comprising a lead body provided with a tapered socket adapted to receive a tapered terminal member, the socketed part having means wholly embedded therein for preventing spreading by the outward pressure of the tapered terminal member.
12. A terminal connector for storage batteries comprising a body having a portion provided with a tapered socket adapted to receive a tapered terminal member, said body being formed of non-corrodible metal having wholly embedded therein a member of relatively hard metal surrounding the socket.
13. A terminal connector for storage batteries comprising a body adapted to be attached to a battery terminal and having a portion provided with a tapered socket, a tapered terminal member fitted in the socket, means for drawing the terminal member against the tapered wall of the socket, said socketed part being provided with a metal re-inforcing ring which is wholly embedded therein and is located wholly outside of the tapered wall of the socket.

In witness whereof, I hereunto subscribe my name, as attested by the two subscribing witnesses.

JOSEPH BIJUR.
